CLAIM

The ornamental design for a container lid as shown and described.

DESCRIPTION

FIG. 1 is a perspective view of a container lid of the present design;

FIG. 2 is a top view of the container lid of FIG. 1;

FIG. 3 is a right side view of the container lid of FIG. 1;

FIG. 4 is a left side view of the container lid of FIG. 1;

FIG. 5 is a front view of the container lid of FIG. 1;

FIG. 6 is a rear view of the container lid of FIG. 1; and,

FIG. 7 is an environmental perspective view of the container lid of FIG. 1.

The portions shown in dashed broken lines depict environmental structure and form no part of the claimed design. Applicant disclaims all views of the container lid not shown in FIGS. 1-7 of the drawings.

1 Claim, 2 Drawing Sheets

Related U.S. Application Data

continuation of application No. 16/502,168, filed on Jul. 3, 2019, now Pat. No. 11,001,413, which is a continuation of application No. 15/464,823, filed on Mar. 21, 2017, now Pat. No. 10,384,834, which is a continuation-in-part of application No. 14/701,961, filed on May 1, 2015, now Pat. No. 9,630,747.
